UNITED STATES PATENT OFFICE

CHARLES OSCAR REEPS, OF CHICAGO, ILLINOIS, ASSIGNOR TO THE AMERICAN LAUNDRY MACHINERY COMPANY, OF CINCINNATI, OHIO, A CORPORATION OF OHIO

WASHING MACHINE

Application filed October 28, 1926. Serial No. 144,669.

This invention relates to washing machines and more particularly to clothes washers, although it may be employed with equal advantage for other purposes.

5 It contemplates more especially the provision of a machine capable of accommodating a plurality of containers, each of which has a multiple of compartments to receive various classes of clothes therein for enabling 10 individual treatment to each.

Numerous devices of the character mentioned have heretofore been proposed, but these have not proven entirely satisfactory due to the inability of removing each customer's washing in bulk with the container as well as to afford individual treatment to each 15 class of clothes. This is necessary or at least highly desirable in order to procure the best and most satisfactory results both from a 20 standpoint of cleansing and mechanical efficiency.

Further, known appliances necessitate much labor, which not only is expensive but also unsatisfactory for the reason that they 25 require a great deal of preliminary clothes sorting with identification markings applied thereto, which gives rise to frequent mistakes and losses resulting from unauthorized taking.

30 One object of the present invention is to simplify the construction and improve the operation of devices of the character mentioned.

Another object is to provide means for accommodating a plurality of freely removable containers wherein each customer's clothes is individually handled and cleansed.

Still another object is to provide a container having multiple compartments insertable as a unit in a machine capable of receiving a plurality of such containers.

A further object is to provide a machine wherein numerous batches of clothes may be washed in individual containers which are 45 freely removable therefrom.

A still further object is to provide a machine wherein numerous batches of clothes may be washed in individual containers which have the contents thereof divided into compartments, each being subjected to a particular cleansing fluid. 50

Other objects and advantages will appear from the following description of an illustrated embodiment of the present invention.

In the drawings:

Figure 1 is a sectional view in elevation of a machine embodying features of the present invention. 55

Figure 2 is a sectional view in elevation taken substantially along line II—II of Figure 1. 60

Figure 3 is a sectional view of a container used in conjunction with the machine disclosed in Figure 1.

Figure 4 is a side view in elevation of the container shown in Figure 3. 65

Figure 5 is a fragmentary view of the container shown in Figure 4, viewed substantially from line V—V of Figure 4.

Figure 6 is a fragmentary view of a container showing a lock construction constituting means whereby the containers are secured to the rotor of the machine. 70

Figure 7 is a sectional view taken substantially along line VII—VII of Figure 6. 75

The structure selected for illustration comprises a cylindrical casing 10 having circular end closures 11 which are centrally apertured to receive axially aligned bearings 12 comprising part of the casing supports 13 to 80 which the standards 14 are secured in any appropriate manner for elevating the casing from the floor or other structure upon which the standards rest. It is to be noted that the casing 10 may be composed of any suitable 85 material, preferably of Monel metal which is non-corroding, unaffected by cleansing fluids, and possesses the required strength.

A drive shaft 15 extends through the casing 10, it being journaled in the bearings 12 90

axially thereof to receive in this instance a spur gear 16 secured to an extremity thereof which projects beyond the bearing 12. The spur gear 16 meshes with a pinion 17 which is fixed to a shaft 18 journalled in appropriate bearings 19' and 20' preferably in rigid association with the casing supports 14 at either end of the casing 10, thereby rigidly supporting the shaft 18 which is connected to 10 any suitable source of power such as an electric motor (not shown).

To enable numerous batches of clothes to be individually and simultaneously washed, the casing 10 may be of any desired length to 15 accommodate any number of containers in tandem, in this instance two, the individual containers being spaced about the shaft 15 in a manner hereinafter described.

As shown, the shaft 15 constituting a part 20 of the rotor, is provided with spaced shoulders 19, 20, 21, and 22, to which the parallel spaced, confronting discs 23, 24, 25, and 26, respectively, are keyed or otherwise secured to constitute confining members for the containers to be described hereinafter. The discs 23, 24, 25, and 26, are apertured at spaced points about the axis thereof as at 27 to define radially projecting ribs or arms 28, in this instance, four thereby materially lightening 30 the construction without impairing the strength thereof. Surrounding the shaft 15 intermediate the discs 23 and 24, 25 and 26, are the tubular members 29 and 30, preferably of non-corroding metal, which are secured at 35 their extremities to the shoulders 19 and 20, 21 and 22, respectively, in any appropriate manner. The tubes 29 and 30 are preferably hermetically sealed to the shoulders to prevent the fluid contained in the casing 10 from 40 reaching the shaft 15 along which it would otherwise flow and find its way through the bearings 12. Secured to the confronting faces of the radially disposed ribs 28 constituting part of the discs, are the laterally projecting members or strips 31, which extend 45 radially between the members 29 and 30 to the periphery of the discs 23—24 and 25—26. The discs 23—24 and 25—26 receive the containers 32 therebetween, in this instance eight, 50 which are spaced about the driving shaft 15 in operative connection therewith owing to the strips 31 which maintain the containers in spaced relation for movement in unison with the rotor.

55 The containers, in this instance, are provided with inclined radially disposed sides 33 and 34 preferably of solid metallic construction which are joined at their converging extremities by a substantially flat member 35 disposed normal to the bisector of the angle defined by the inclined sides, the member 35 contacting with the tubular members 29 or 30 which envelops the shaft 15. The diverging extremities of the sides 33 and 34 60 terminate in parallel spaced apertured por-

tions 36, in this instance disposed normal to the side 35 thereof and extending substantially to the periphery of the discs 23—24 and 25—26, between which they are confined. As shown, the portions 36 have an arcuate apertured closure 37 associated therewith, the curvature thereof conforming with the periphery of the discs to which the containers are selectively locked to prevent outward movement occasioned by the action of centrifugal force in consequence of the rotary movement imparted thereto.

The end walls 38 and 39 of the containers 32 are also of solid metallic construction, they being secured to the component parts of the container in any suitable manner such as by means of the angular members 40 constituting reinforcing edges therefor. An inclined wall 33 of the container 32 is preferably hinged to the portion 36 thereof as at 41 in the usual manner, the opposed side thereof being provided with a lock 42 of standard construction whereby each container may be provided with different locks to prevent the unauthorized opening thereof or the placing 55 of clothes in the wrong bag for delivery, since it is proposed to have a key individual to each customer.

The locking means employed for preventing outward movement of the containers during the rotation thereof, comprises a plate 43 riveted or otherwise secured to the apertured side 37, in this instance along a median line thereof, adjacent the end walls 38 and 39. As shown, the plate 43 has a depressed portion 44 wherein a slidable lock bolt 45 is mounted to normally project outwardly by the action of an appropriate spring 46 interposed between an abutment 47 integral with the depressed portion 44, and the shank 48 of the bolt 45 which has a portion 49 projecting above the abutment 47 to prevent the spring from moving upwardly. The lock bolt 45 projects through the end wall and reinforcing edge 40 of the container, it being lodged in a suitable slot 50 provided in the discs 23—24 and 25—26 which confine the containers 32 therebetween. To retract the bolt 45 so as to permit the removal to the containers 32 from the rotor, a handle 51 is pivotally mounted 105 in the depressed portion 44 of the plate 43 by means of a pin 52, there being a slot 53 in the bolt 45 wherein the angularly disposed extremity 54 of the handle 51 projects so as to cam the lock bolt 46 inwardly against the 110 action of the spring when the handle 51 is pulled upwardly, thereby releasing the container from the rotor responsive to movement of the handles occasioned by exerting a lifting pull thereon. It will be understood that 115 the handles 51 are normally maintained within the depressed portion 44 of the plate 43 by virtue of the spring 46 which simultaneously urges the bolt 45 outwardly to locking position. In the present embodiment each 120

container 32 is provided with two such locking instrumentalities arranged along the median line or the arcuate side 37 adjacent the ends 39 and 40 thereof to engage the discs 5 23-24 or 25-26 between which they are confined.

The containers 32 are freely removable through an opening 55 provided in the casing 10, which is of such size as to permit the 10 containers to be individually removable therethrough. To prevent the escape of the cleansing fluids contained in the casing 10, through the opening 55 as well as to make it impossible for foreign substances to enter 15 therethrough, a closure 56 is slidably mounted on the interior of the casing to be selectively movable to cover the opening 55 which, in this instance, is disposed at the top of the casing 10.

20 With the arrangement of parts thus far described, it will be apparent, that novel means have been provided to freely receive a plurality of individual, removable containers 32 constituting complementary circular segments arranged about a driving shaft 15 to be periodically immersed in the cleansing fluid which partially fills the casing 10. Upon rotation of the containers 32 containing clothes 56' therein, the cleansing fluid will 25 be projected into the containers through the sides 36 and 37 thereof, the sides 36 being angularly disposed with the corresponding sides of the next succeeding container so as to present a free liquid space therebetween 30 to force the cleansing fluid through the apertures therein responsive to the rotation thereof. This is especially effective, since the sides 36 are disposed within the path of the fluid, the apertures therein being somewhat larger 35 in size than those provided in the arcuate end closure 37 thereof.

Obviously, by moving the closure 56 of the casing 10 to its open position, and stopping the rotation of the containers 32, the latter 40 may be conveniently removed by grasping the handle 51 thereof to lift the particular container through the opening 55 whereupon the locking bolt 45 is instantly retracted to permit the removal of the container from the 45 confining sides 23 and 24 or 25 and 26.

It has long been the practice to sort the various batches of clothes belonging to each customer into various classes to enable each 50 to be subjected to a different cleansing treatment. In practice, it has been found that the division usually consists of three classes comprising clothes which may appropriately be classified as light, light color, and dark color, 55 which classification is according to colors and texture. Assuming that three classes will suffice, it is the purpose of this invention to divide each container into a plurality of compartments wherein the various classes of 60 clothes may be subjected to individual treat-

ment best suited to accomplish the desired end.

Accordingly the containers 32, in this instance, are divided into three compartments, 57, 58 and 59. As shown, the compartments 70 constitute individual units spaced from each other to define raceways 60 and 61 therebetween the compartments being secured together to form a rigid unit by means of the spacing blocks 62 positioned at the inner end 75 of the compartments in proximity to the driving shaft 15. The spacing blocks 62 have an arcuate surface 63, and are held rigid with the compartments by means of rivets or other suitable fasteners 64, it being understood 80 that each compartment has a hinged closure 33 as described in connection with the container 32, *supra*.

Fixed to the interior of the casing 10 in any appropriate manner are partitions 65, 66, 67, 68 and 69 which, in this instance, extend upwardly for a distance nearly approaching the horizontal diameter of the casing 10, the partitions terminating in a horizontally disposed edge 70 having an intermediate arcuate 85 recessed portion 71 conforming in curvature to the arcuate surface 63 of the spacing block 62 which approach each other in confronting relation, which may, if desired, be in frictional contact, should commercial practice 90 dictate; however, it has been found that this is not necessary to effectively segregate the casing 10 into separate cleansing fluid compartments. With this arrangement, the partitions are spaced to project within the raceways 60 and 61 defined by the spaced compartments constituting the containers 32, the partition 67 in the present embodiment, segregating the casing 10 into two portions of 95 equal size so that two batteries of containers 100 may be arranged in tandem as described above. A circular spacing block 72' is secured intermediate the discs 24 and 25 to the axis thereof to co-operate with the partition extremity 67 to prevent intermingling of the 105 cleansing fluids contained in adjacent fluid compartments defined by the partition 67, in much the same manner as do the spacing blocks 62 interposed between the compartments of each container. 110

With this arrangement of parts it will be apparent that each customer's clothes may be washed in an individual container having compartments arranged to receive the various classes of clothes which are subjected 115 to different fluids most effective for cleansing them, there being no intercommunication between the fluid compartments provided within the casing 10 owing to the novel arrangement of parts above described. Obviously, the casing 10 may be made of such size as to accommodate any number of container batteries in tandem, and each container may be varied in size and angularity so that any number 120 may be arranged about the driving shaft 125

to accommodate sufficient containers to suit the needs of a commercial laundry.

It will be evident from Figure 3 that the perforations in the upper side 37 of each compartment are substantially smaller than the apertures in the parallel sides 36 of the compartment. In fact, the perforations in the side 37 are not essential to the washing operation. These perforations are merely provided so that the same compartment can be used in an extractor such as that disclosed in my co-pending patent application Serial No. 145,433, filed November 1st, 1926.

The perforated parallel sides 36 of each compartment afford substantially the sole means for the washing fluid to enter and leave the compartment. From Figure 2 it will be evident that as the shaft 15 rotates, each compartment is brought into a position wherein one of its parallel sides 36 is disposed so as to face the fluid in the bottom of the cylindrical casing 10. Continued rotation of the shaft results in this perforated side 36 being forced downwardly into the fluid, resulting in the fluid entering the compartment with a terrific force. It is this feature which enables the machine of my invention to wash clothes in much less time than any other washing machine which I have come in contact with.

After the compartment has moved through the fluid in the bottom of the casing, its other parallel and perforated side 36 is brought into a position wherein it leaves the surface of the fluid in the casing. It is while the compartment is in this position that the liquid tends to leave the compartment. However, it is to be noted that due to the clothes resting on the side 36 of the compartment adjacent the fluid, considerable of the washing fluid is retained in the compartment so that as it travels upwardly around the axis of shaft 15, the clothes are still being washed in fluid. Now it will be evident from the illustration in Figure 2 that the clothes 56 in any one compartment are adapted to be forced into at least four different positions during one complete rotation of the shaft 15. These four different positions of the clothing 56 are clearly shown in Figure 2. This movement of the clothing augments the washing of it and hence enables the machine to turn out completely washed work in a minimum of time.

To facilitate the convenient admission and discharge of the fluids, an inlet pipe 72 is connected to each fluid compartment of the casing 10 in any suitable manner, it being properly valved to control admission from the supply source to which they are connected. Discharge is effected through pipes 73 which communicate with the bottom of each fluid compartment so as to enable them to be selectively emptied, the used cleansing fluid being directed to a filtering plant or sewer as

may be found desirable. An overflow drain 74 is disposed above the supply pipe 72, at the desired liquid level so as to prevent the admission of a quantity of fluid greater than that which is compatible with efficient operation. 70

I am aware that many changes may be made and numerous details of the construction may be varied through a wide range without departing from the principles of this invention, and I therefore do not purpose 75 limiting the patent granted hereon, otherwise than necessitated by the prior art.

I claim as my invention:

1. A container for a washing machine, comprising movable closure means, radially disposed sides inclined toward each other at one end and terminating at the other end in parallel extensions having apertures therein, an arcuate apertured wall disposed between said extensions and end pieces connected to 85 said sides.

2. A container for a washing machine, comprising radially disposed sides inclined toward each other at one end and terminating at the other end in parallel extensions 90 having apertures therein, an arcuate apertured wall disposed between said extensions, end pieces connected to said sides one of said sides being hinged to constitute a closure, and locking means for said closure. 95

3. In a washing machine, the combination with a casing, a driving shaft rotatably disposed therein, a plurality of longitudinally spaced partitions connected to the periphery of said casing, said partitions extending to 100 a point removed from said shaft, and a container rotatable by said shaft and comprising spaced compartments arranged to be positioned in said casing with the partitions projecting therebetween. 105

4. In a washing machine, the combination with a casing, a driving shaft rotatably disposed therein, partitions fixed to said casing, a plurality of containers spaced about said shaft, said containers comprising a plurality of spaced compartments receiving the partitions therebetween, and means radiating 110 from said shaft for separating and revolving said containers in unison with said shaft. 115

5. In a washing machine, the combination with a casing, a driving shaft rotatably disposed therein, partitions fixed to said casing, a plurality of containers spaced about said shaft, said containers comprising a plurality of spaced compartments receiving the partitions therebetween, means radiating from said shaft for separating and revolving said containers in unison with said shaft, each of said compartments having apertured 120 arcuate sides conforming in curvature with that of said casing, and means for locking said containers in said casing. 125

6. In a washing machine, the combination with a casing, a driving shaft rotatably dis- 130

- posed therein, partitions fixed to said casing, a plurality of containers spaced about said shaft, said containers comprising a plurality of spaced compartments receiving the partitions therebetween, means radiating from said shaft for separating and revolving said containers in unison with said shafts, each of said compartments having apertured arcuate sides conforming in curvature with
- 6 that of said casing, means for locking said containers in said casing, said containers having inclined radially disposed sides, and apertured portions angularly disposed to the radial sides of the containers.
- 10
- 15 7. In a device of the character described, a framework, means associated with said framework for holding a plurality of cleansing fluids, a plurality of containers removably mounted in said framework, each of said
- 20 containers being provided with a plurality of compartments, and means for effecting relative movement of the containers with respect to the framework to simultaneously subject each compartment of one container to
- 25 a different cleansing fluid.
8. In a washing machine, a casing, a shaft mounted in said casing, a removable container mounted on the shaft including a plurality of spaced integral compartments, and
- 30 a partition connected to said casing and extending inwardly toward said shaft and into a space between said compartments, each of said compartments including sides extending substantially radially from said shaft
- 35 and perforated sides, each of which is disposed at an angle to one of said radial sides and adjacent the inner periphery of the casing.
9. As an article of manufacture, a container adapted for use in a washing machine having a cross section substantially like a segment and being defined by upwardly diverging sides connected at the bottom of the container, movable closure means for said
- 40 container, parallel sides connected to the upper extremities of the diverging sides, a side connecting the parallel sides, and end pieces connected to said sides, said parallel sides being each perforated to allow washing fluid
- 45 to enter and leave the container during the washing operation.
10. In a washing machine, a housing, a rotatable shaft associated with said housing, a plurality of perforated containers in said
- 55 housing, each being removably connected to and rotatable by said shaft and including a plurality of spaced integral compartments and a partition connected to said housing and extending inwardly towards said shaft
- 60 and adapted to project into a space between said compartments of each container as the containers are rotated by said shaft.
11. As an article of manufacture, a container for use in laundry machines of the
- 65 type described comprising diverging sides
- having their adjacent extremities connected together, substantially parallel perforated sides connected to the other extremities of said diverging sides, a side connecting the parallel sides, end walls connected to said sides, and means for movably supporting one of said sides to permit of its movement away from the other sides to afford access to the interior of said container.
- In testimony whereof I have hereunto subscribed my name.
